Des. 203,335
Patented Dec. 28, 1965

203,335

BUILDING ADAPTED FOR USE AS A CHILDREN'S SHOE STORE OR THE LIKE

Lawrence T. Hord, Jr., Memphis, Tenn., assignor to Raiford's, Inc., Memphis, Tenn., a corporation of Tennessee

Filed Feb. 3, 1965, Ser. No. 83,674

Term of patent 14 years

(Cl. D13—1)

Fig. 1

Fig. 3

FIG. 1 is a side elevation of a building of my design for use as a children's shoe store or the like.

FIG. 2 is a front elevation.

FIG. 3 is a top plan view.

FIG. 4 is a perspective view from the rear and to one side of the building, and

FIG. 5 is a perspective view from the front and to one side of the building.

I claim:

The ornamental design for a building adapted for use as a children's shoe store or the like, as shown and described.
